UNITED STATES PATENT OFFICE.

ALBERT EBNER, OF STUTTGART, WURTTEMBERG, GERMANY.

AUTOMATIC STOP MECHANISM FOR TALKING MACHINES.

Application filed September 14, 1920. Serial No. 410,332.

To all whom it may concern:

Be it known that I, ALBERT EBNER, a citizen of the German Empire, residing at Stuttgart, Wurttemberg, Germany, have invented certain new and useful Improvements in Automatic Stop Mechanism for Talking Machines, of which the following is a specification.

In order that it may not be necessary in 10 talking machines to watch for the end of a record for the purpose of removing the needle from the last groove devices have been suggested which stop the talking machines automatically by means of electric contacts. The known devices of this kind 15 however, are troublesome alike in their structure as in their working, so that disturbances in the working easily occur.

This invention relates to a device, which 20 is distinguished by its great simplicity in every respect, works perfectly reliably, and moreover has the advantage of being adjustable.

The invention consists substantially in the 25 circuit of the driving motor being automatically interrupted by the intermediate circuiting of a suitably formed contact device in that position of the sound arm in which the needle is in the last groove of 30 the disc. Through the turning of the sound arm with the needle inwards a contact moves on a contact strip, the end of which is so arranged or can be so placed, that the contact slides off the strip, as soon as the needle 35 of the sound arm is in the last groove of the disc.

Now in order to effect a sudden interruption of the contact, the sliding contact device is constructed as a lever contact device, 40 in connection therewith the current is interrupted by putting the contacts apart. The contact lever lies ordinarily on a free contact and is removed by the sound arm at the moment when its needle has reached 45 the end of the grooves in the record. The lever is suitably formed with a bend that lies in the path of the sound arm or of an extension of the same. When the sound-arm has been turned back into the starting position the contact lever returns at once into the contact closing position, in connection 50 therewith however the current is suitably switched on by a special switch situated in the circuit.

55 The adjustment for the commencement is

effected precisely as with the sliding contact device.

The arrangement can be improved further so that injury to the disengaging or stopping device is avoided, as frequently happens through unskillfulness or inattention since the contacts which come on to the other are damaged if too great force is used.

The improvement consists in the form of the contact-piece which is actuated by the sound arm, for the purpose of interrupting the current, allowing the disengaging pin or the like arranged on the sound arm to be carried over the contact piece and notwithstanding to actuate the latter, as the contact piece is furnished with an oblique sliding surface for the pin or the like of the sound arm, which, when running on to this surface, breaks the circuit by turning the contact piece and then, as the sound arm further rotates, slides away over the contact piece. If the contact piece be sloped also on the other side, the device can be employed after the contact device has been turned round without further trouble in the same manner as for sound discs in which the grooves run in the opposite direction.

The object of the present invention is shown in the drawing in different forms by way of example,

Fig. 1 is a side elevation of the new arrangement of the one form of construction partly in vertical section.

Fig. 2 is a plan as seen when the action begins.

Fig. 3 a partial elevation, partly in section, of a second form of construction.

Fig. 4 an under-plan of the interrupting device.

Fig. 5 is the plan of the contact device again of a different form of construction.

Fig. 6 a plan of a further form of construction, and

Fig. 7 a side elevation of the same.

On the base 1 in which the sound arm 2 is pivotally mounted in the known manner, is an insulating body 4 in the form for example of a bell which is carried by an arm 3, and can be rotated around a shaft 5. The bell is arranged with such friction that it remains stationary in any position of rotation. The rotation itself is facilitated by a roughened surface 6 for holding the bell formed in the upper part as a head 7. In this bell 4 in the form of construction shown

in Figs. 1 and 2 is a current conducting piece 8, which is constructed as a segment and is formed as portion of a circle struck from the axis 5 of the bell 4, as shown in Fig. 2. This segment 8 is conductively connected with the cable 10 through a conductor 9.

On the sound arm 2, insulated by a support 11, a current conductor 12, for example 10 a carbon is arranged, which is pressed by a spring 13 against the segment 8 and the under surface of the bell 4. The conductive holder or socket 14 of the sliding carbon 12 is in conductive connection with the other 15 cable 15, so that the current is switched on and the motor runs, as soon as the carbon is on the segment 8, and as long as it runs thereon.

The length of the segment 8, as well as its 20 starting and end points are arranged in relation to the carbon 12 in such a manner that the latter runs down from the segment and is pressed against the lower surface of the bell 4 consisting of insulating material, 25 when the piece of music comes to an end, that is to say when the needle is in the last groove of the sound disc (not shown). Thereby, at this moment, the current is 30 switched off and the motor mechanically stopped.

Now in order to take into account the different lengths of the pieces of music, that is to say the different position of the last groove more or less far in, an adjusting device is provided, by which the carbon 12 and therewith the sound arm 2 can be given the right position in relation to the end of the segment 8. For this purpose, on the bell is a notch 17 and on the sound arm 2 a pointer 40 18 which at the same time can form the base-plate of the carbon holder 14. The notch 17 has such a position in relation to the end of the segment 8 that the carbon 12 runs down from this, if the notch 17 and pointer 18 45 coincide.

Before the beginning of the reproduction of a piece of music the needle is inserted in the last groove of the sound disc and the bell then rotated until the notch 17 coincides 50 with the pointer 18.

The sound arm 2 is now turned back and if necessary inserted in the extreme outside groove in the disc. With suitably long segment 8 the carbon 12 is then on the segment 55 8 and the current is thereby switched on. According to the length of the piece of music a more or less long course of the segment 8 is run over by the carbon 12 in this way until the current is switched off, in connection wherewith each time the end of the same 60 is brought into coincidence with the last groove in the disc.

A further hand operated switch of any suitable construction is further introduced 65 into the circuit, and by means thereof the

circuit can be a second time interrupted or closed. In order to set the arrangement in action, the second switch is then put in circuit and the sound arm then only moved against the disc, whereby the sliding carbon 12 slides gradually on the segment 8 and sets the disc in motion.

The order in which the switching on takes place can be equally well reversed. The form of the bell 4 and of the segment 8 are optional, in whatever manner the contact device may be otherwise formed.

In the form of construction according to Fig. 5 a contact lever 20 is arranged on the segment 8 and so as to pivot around a pin 19. This lever which is in conductive connection with the segment 8 is constantly pressed by a spring 21 against a contact piece 22, which is connected with the source of current through a conductor 15. The two contacts 23 then lie one on the other, so that the circuit is closed and the sound disc rotates.

On to the contact lever 20, which is furnished for the purpose with a standing off arm 24, the sound arm 2 now comes with the assistance of a suitable insulated extension 25, whereby the circuit is interrupted and the apparatus stopped. By suitable adjustment of the parts this shutting or switching off 95 that is to say the coming of the sound arm 2 on to the contact lever 20 occurs at the moment when the piece of music is played to the end.

In the form of construction shown in Figs. 6 and 7 the contact lever 20 is arranged to pivot around a horizontal shaft 19 and presses against a second segment 22, which takes the place of the contact piece 22 in the form shown in Fig. 5.

The form of construction according to Figs. 3 and 4 employs a contact lever 20, which is provided with an enlarged portion or cam 26 for engagement with the switching-off pin 25 or the like arranged on the sound arm 2 and is so arranged that the pin 25 slides across the prominent portion of the cam and presses the lever inwardly to separate the contacts 23. It is possible for the pin 25 of the sound arm 2 to move past the cam 26 on to the other side of the contact piece 20.

To adapt the device for use in connection with discs or records by which the tone arm 2 is fed outwardly with relation to the axis of the disc, instead of inwardly, both sides of the cam 26 are correspondingly inclined for cooperation with the pin 25 of the sound arm 2, regardless of the direction of movement of the latter.

In the latter case the bell 4 is rotated towards the other side.

I claim:—

1. In an automatic stop device for talking machines of the electric motor driven type 130

equipped with a movable tone arm, contact members adapted to be interposed in the electric motor circuit, one of said contacts being actuated by the tone arm, means permitting adjustment of the other contact whereby the moment of separation of the contacts may be varied according to the position of the end of the sound groove in the record, and indicating means facilitating correct adjustment of the adjustable contact to effect separation of the contacts at a predetermined point with respect to the sound groove in the record.

2. In an electric motor stop device for talking machines of the electric motor driven type equipped with a movable tone arm, a pair of contacts adapted to be interposed in the electric motor circuit, one of said contacts being actuated by the tone arm to effect its separation from the other contact, and a rotatably mounted support for the other contact mounted for adjustment whereby the moment of separation of the contacts with respect to the position of the tone arm may be varied according to the length of the sound groove in the record.

3. In an electric motor stop device for talking machines of the electric motor driven type equipped with a movable tone arm, a contact member carried by the tone arm, a second contact engageable with the first contact, said contacts being adapted to be interposed in the electric motor circuit, and a rotatably adjustable support for the second contact having its axis of rotation coincident with the axis of movement of the tone arm whereby the moment of separation of said contact may be varied with respect to the position of the tone arm according to the length of the sound groove in a record.

4. In an electric motor stop device for

talking machines of the electric motor driven type equipped with a movable tone arm, a pair of contacts adapted to be interposed in the electric motor circuit, an adjustable support for one of the contacts, the other contact being actuated by the tone arm, and means on the tone arm for indicating the position of the contact member actuated thereby with respect to the adjustable contact member.

5. In an electric motor stop device for talking machines of the electric motor driven type equipped with a movable tone arm, a pair of contacts adapted to be interposed in the electric motor circuit, a lever supporting one of the contacts, means carried by the tone arm for actuating said lever to disengage the contact member carried thereby from the other contact member, and an adjustable support for said other contact member for varying its position with respect to the first mentioned contact member.

6. In an electric motor stop device for talking machines of the electric motor driven type equipped with a movable tone arm, a pair of contact members adapted to be interposed in the electric motor circuit, an adjustable support for one of said contact members, a lever supporting the other contact member and normally maintaining the latter in engagement with the first contact member, and means attachable to a tone arm for engaging and actuating said lever during movement of the tone arm in either direction.

In testimony whereof I hereby affix my signature in presence of two witnesses.

ALB. EBNER.
